TREATMENT OF HYDROCARBONS

Robert Pyzel, Chicago, Ill., assignor to Universal
Oil Products Company, Chicago, Ill., a corpora-
tion of Delaware

Application May 31, 1938, Serial No. 211,066

5 Claims. (Cl. 196—41)

This invention relates to the treatment of the lower boiling range hydrocarbons produced in the cracking of the relatively heavy portions of petroleum oils.

5 It is more specifically concerned with a treatment applicable to the cracked gases and naphthas of gasoline boiling range to effect a partial purification thereof and the simultaneous production of a relatively narrow cut of normally 10 gaseous olefin-containing hydrocarbons comprising principally 4-carbon atom hydrocarbons, which is sufficiently purified so that it exerts substantially no poisoning influence on catalysts subsequently employed to polymerize its olefinic 15 content and produce gasoline boiling range olefins which are hydrogenatable to corresponding paraffins of relatively high antiknock value.

Petroleum refiners are concerned at the present 20 time with the more effective utilization of the gaseous by-products of cracking petroleum fractions for the production of gasoline, and attention has been focused especially on polymerization processes whereby liquid products boiling within the range of motor fuel are produced. These processes may operate upon the 25 cracked gas mixtures as a whole or upon selected fractions of relatively narrow boiling range such as the so-called propane-butane fractions of a still narrower cut comprised principally of both 30 saturated and unsaturated four carbon atom hydrocarbons. Thus far the ethylene content of cracked gases has resisted efforts to convert it directly into gasoline boiling range liquids.

The processes employed at present in converting 35 the three and four carbon atom hydrocarbons of cracked gaseous mixtures into gasoline boiling range material, may be roughly classified as: (1) thermal, and (2) thermal-catalytic, the latter processes operating generally at lower pressures 40 and temperatures and being more specific in their action on the olefinic content of the gas fractions to form liquids of a purely mono-olefinic character. When operating upon gas fractions comprising predominantly butanes and butenes, catalytic polymerizing operations may be so controlled 45 that the major product corresponds to a mixture of dimers of the butylenes which are readily hydrogenatable to mixtures of octanes 50 which have antiknock values approaching that of the standard iso-octane and are hence much sought after as fuel for high compression engines such as those of the airplane type.

One process which has attained extensive com- 55 mercial use in polymerizing normally gaseous

olefins involves the use of solid granular phosphoric acid-containing catalysts.

Catalysts containing phosphoric acid have been found to be particularly effective in respect to their action in producing dimers and trimers of the normally gaseous olefins in preference to polymers of higher molecular weight. However, it has been found that the effective life of these catalysts is frequently seriously reduced by the presence of relatively small amounts of impurities 10 in the olefin-containing hydrocarbon mixtures which they are employed to treat. The exact nature of the poisoning substances is not entirely known, but some experimental and analytical work has indicated that it may be due in part to 15 sulfur compounds of various types and to nitrogen compounds of the nature of ammonia or amines, these last groups being particularly damaging. These nitrogen compounds may arise in various ways. For example, they may have been deliberately introduced into cracking plants as ammonia to reduce corrosion, or they may have resulted in the cracking of nitrogen-containing oils which are frequently encountered in different oil fields. The present process embodies a co-operative combination of treating steps which will both treat 20 cracked gasolines and remove impurities from olefin-containing normally gaseous fractions intended for phosphoric acid polymerizing plants so that substantially increased catalyst life is 25 obtained.

In one specific embodiment the present invention comprises a process for the treatment of unstabilized cracked gasolines and the production of maximum yields of purified butane-butylene 35 fractions suitable for polymerization which consists of the following steps: (1) introducing cracking plant receiver gases to a high pressure absorber in which absorption is effected by debutanized naphtha; (2) introducing unstabilized 40 cracked gasoline along with the rich high pressure absorbing oil to a depropanizer in which propane and lighter materials are removed; (3) subjecting the unabsorbed gaseous products from the high pressure absorber to further absorption 45 in a low pressure absorber wherein the absorber oil is an intermediate fraction of cracked naphtha which is returned to the cracking plant fractionator; (4) cooling and treating the depropanized material with aqueous alkalis; (5) further 50 fractionating the treated naphtha to produce a butane-butylene fraction as an overhead distillate; (6) washing said overhead distillate with water (preferably acidulated); (7) applying a final aqueous alkali wash to the water washed 55

butane-butylene fraction to produce purified material for charging to polymerizing plants employing solid phosphoric acid.

The process as above briefly outlined serves to produce a stabilized and partially purified naphtha which can then be subjected to further treatment for the production of a satisfactory gasoline and a butane-butylene fraction which has been freed from traces of materials having a deleterious effect on phosphoric acid catalysts. It has been found that the sequence of steps outlined is a very practical one and that the caustic washings must be done both before and after a water wash which apparently takes out traces of compounds of an alkaline reaction such as ammonia and amines which are not effectively removed by caustic soda or other alkalis. As will be shown in later examples, the butane-butylene fractions produced by this method can be processed for extended periods of time with no effect on the activity of the phosphoric acid catalyst than the gradual carbonizing which is always noted whereas the untreated fractions cause a quick drop in efficiency which necessitates a plant shut-down and the reactivation or replacement of the catalyst.

The process will be described in greater detail by reference to the attached drawing which shows in general side elevation without regard to any particular scale or relative size of the elements an arrangement of apparatus in which the process may be conducted. It will be evident that the invention is not limited by the exact features shown but that the drawing is merely illustrative of the types of plants employed in the operation.

Referring to the drawing, cracking plant receiver gases which are separated at the primary condensation of the lighter cracked products from a cracking plant are introduced through line 1 containing valve 2 to a pump or compressor 3 which discharges through a line 4 containing a valve 5 through high pressure absorber 6 which receives from line 138 containing valve 139 a portion of the debutanized pressure distillate whose production will be described in sequence at a later point. This absorber is preferably operated at a temperature of approximately 100° F. under a pressure of 250 lbs. per square inch. The unabsorbed gases pass through line 7 containing valve 8 to a low pressure absorber 9 which operates at a pressure of approximately 50 lbs. per square inch at a temperature of 112° F. In this absorber an intermediate fraction from the final cracking plant fractionator is preferably employed as an absorber oil, the source of this material not being shown in the drawing, though line 10 containing valve 11 and leading to pump 12 is indicated as a line for its admission. Pump 12 discharges into the top of the low pressure absorber through a line 13 containing a valve 14. The enriched absorber oil is withdrawn from the bottom of the low pressure absorber through line 15 containing valve 16 and returned through line 18 containing a valve 19 by pump 17 back to the cracking plant fractionator preceding the source of the gases admitted through line 1. By this method of operation substantially all of the three and four carbon atom hydrocarbons in the cracking plant receiver gas are recovered and further processed.

The bottoms from the high pressure absorber 6 which will include all of the four-carbon atom hydrocarbons and substantially all of the three carbon atom hydrocarbons are withdrawn through line 19 containing valve 20 to a pump

21 which discharges through line 22 containing valve 23 and thence into line 27. Unstabilized cracked gasoline from the receiver of the cracking plant is introduced through line 24 containing a valve 25 to a pump 26 which discharges through line 27 containing valve 28, the discharge mixing with the enriched absorbing liquid from high pressure absorber 6 and passing to heater 29 which has an inlet line 30 containing valve 31 for heating fluid and exit line 32 containing valve 33 for allowing its release.

It will be seen from the description of the process up to this point that by the use of a combination of high pressure and low pressure absorbers and absorbing oils that practically all of the three and four carbon atom hydrocarbons produced in the cracking process will be recovered since both the cracking plant receiver gas and the liquid constituting the unstabilized cracked gasoline are processed.

The preheated mixture of high pressure absorber oil and unstabilized cracked gasoline are admitted through a line 34 containing a valve 35 to a depropanizing column 36 which has an upper vapor line 37 containing a valve 38 for the release of propane and light gases. This column is preferably provided with a reboiling device which is indicated in the drawing as being a closed coil 39 having an inlet line 40 containing a valve 41 for the admission of heating fluids and an outlet line 42 containing a valve 43 for their release. This column is preferably operated at a relatively high pressure to permit effective removal of 3-carbon atom hydrocarbons and lighter compounds while retaining substantially all of the butanes and butenes. The column may be equipped with conventional reflux return to the top.

Bottoms from depropanizer 36 which will be at a temperature of approximately 360° F. are now cooled and subjected to a treatment with an alkaline aqueous solution, usually caustic soda. Thus they are removed through line 44 with valve 45 closed to line 46 containing valve 47 and passed through a cooler 48 which has an inlet line 49 containing a valve 50 for the admission of cooling liquids and an exit line 51 containing valve 52 for their release. The bottoms from the depropanizer are thus preferably cooled to a temperature of approximately 120° F. and are then conveyed through line 53 containing valve 54 to the inlet of a mixer 55 which receives recirculated caustic soda from line 131 containing a valve 132. The recirculated caustic soda and depropanized material passing through mixing device 55 and line 56 containing a valve 57 to settling tank 58 is withdrawn by pump 130 by way of line 124 containing valve 125 and line 128 containing valve 129. A certain amount of the recirculated caustic is continuously wasted through line 126 containing valve 127, the makeup coming from points to be later described.

This primary caustic washing has the effect of removing traces of hydrogen sulfide and some low boiling mercaptans from the depropanized naphtha and in the next step of the process the partially purified material passes from settling tank 58 through line 59 containing valve 60 to further fractionation. It is first heated to a temperature of approximately 210° F. during passage through a heater 61 which has a heater coil such as a steam coil with an inlet line 62 and a valve 63 and a waste line 64 containing valve 65. The heated material follows line 66 containing valve 67 and enters line 44 leading to debutanizer 68.

It will be noted that valve 45 may be used as a by-pass valve in line 44 to permit the omission of the first caustic washing step either in whole or in part if this is found feasible.

5 Debutanizer 68 is preferably operated at a top temperature of 150° F. under a pressure of 100 lbs. per square inch, this column also being provided with a reboiling device 69 with an inlet line 70 containing a valve 71 for heating fluids and an 10 exit line 72 containing a valve 73 for their release. The bottom temperature is maintained in the neighborhood of 300° F. The material drawn through the bottom of the column through a line 14 containing valve 75 will consist of stabilized 15 naphtha which is amenable to any further chemical treatment and distillation to produce a gasoline of some desired boiling range. This material is taken by pump 133 and discharged through line 134 containing valve 135. Whatever portion is 20 not to be used as absorbing oil in the high pressure absorber is withdrawn to storage through line 136 containing valve 137. That portion which is used in the high pressure absorber is passed through line 138 containing valve 139 to the top of column 6.

25 The overhead from debutanizer 68 preferably consists of 4-carbon atom hydrocarbons comprising butanes and butylenes which pass through line 76 containing valve 77, through a condenser 78 and thence through rundown line 79 containing valve 80 to a receiver 81 which has a conventional gas release line 82 containing a valve 83. The liquid contents of receiver 81 are taken by pump 86 by way of line 84 containing valve 85 and distributed in part through line 87 containing valve 88 back to the top of the debutanizer to assist in controlling the composition of the emergent vapors and in part through line 89 containing valve 90 to the final purification steps.

40 At the entrance to mixer 91 the butane-butylene fraction meets a stream of water which is preferably slightly acid and which is supplied by pump 94 which takes suction on a source of supply through line 92 containing valve 93 and discharges through line 95 containing valve 96. The mixture of water and butane-butylene fraction from mixer 91 passes through line 97 containing a valve 98 to settling tank 99 which is provided 45 with a draw-line 100 containing valve 101 for the removal of the wash water.

45 The apparent reason for the necessity of the water wash has already been explained. The amount of water necessarily to effectively purify 50 the butane-butylene fractions will vary with the amount of water soluble materials and no absolute rules can be laid down. As a rule best results are obtained by the use of a moderately large percentage by volume and the use of water 55 which is not alkaline as are some natural waters, and which may be advantageously somewhat acidic.

55 The partially purified butane-butylene fraction from settling tank 99 passes through line 102 containing valve 103 to a third mixer 104 at the entrance of which it receives an addition of alkali solution consisting both of fresh and of 60 recirculated material. The fresh material is taken by pump 112 through line 110 containing valve 111 and discharged through line 113 containing valve 114 into line 115. The recirculated material comes from final settling tank 107 65 through line 108' containing valve 109' and line 117 containing valve 118 to pump 119 which discharges into line 115 containing valve 116. The

70 mixture of alkali and butane-butylene fraction then passes finally to settling tank 107 through line 105 containing valve 106 and may be withdrawn therefrom by way of line 108 containing valve 109 for charging to the polymerizing plants 75 mentioned. A portion of the settled aqueous layer from tank 107 may be passed through valves 109' and 120 in line 108' to pump 121 and discharged through line 122 containing valve 123 into the primary mixer 55 along with caustic 80 recirculated from settling tank 58.

85 The following experimental data is introduced to indicate the order of improvement experienced in the use of phosphoric acid-containing polymerizing catalysts when the olefin mixture 15 charged is treated by the process of the invention, although it is understood that the exact comparison given only holds for one particular charge and the scope of the invention is not to be taken as limited thereby.

90 The receiver gas and receiver liquid constituting unstabilized cracked gasoline from a cracking plant operating on a West Texas charging stock were subjected to the cycle of operations described in connection with the drawing, the 25 receiver gases being introduced through a high pressure absorber wherein substantially all three and four carbon-atom hydrocarbons were absorbed by debutanized distillate and the unstabilized cracked gasoline mixed with the pressure 30 absorber liquid, preheated and introduced into the depropanizer and subjected to the cycle of operations already described to produce a purified butane-butene fraction. When subjecting the purified material to contact with a granular 35 solid phosphoric acid catalyst to produce a mixture of octenes from the butene content it was found that approximately 90 gallons of liquid hydrocarbons could be produced per pound of catalyst before there was appreciable deterioration 40 thereof as measured by the rate of conversion of olefins. The tests were conducted under conditions in the catalytic zone of approximately 330° F. and 650 lbs. per square inch pressure.

45 Using a butane-butene fraction originating from the same source, but produced by ordinary methods without the combination of caustic, water, and caustic washing, it was found that a production of approximately 20 gallons per pound 50 of catalyst was all that could be obtained before there was a serious deterioration in the polymerizing capacity of the catalyst.

55 It is presumed in the absence of completely confirmatory data that the reason for the necessity of the intermediate water wash is due to traces of basic substances such as ammonia and amines which combine directly with the active phosphoric acid in the granular catalyst and quickly render it catalytically inert. Even though analyses show only traces of these compounds in many instances, they seriously affect the acid catalyst quite out of proportion to the quantity present.

60 The scope of the described invention is shown clearly by the above specification and numerical 65 data neither of which is intended to be unduly limiting.

65 I claim as my invention:

70 1. A process for the production and purification of butane-butene fractions to render them suitable for contacting with a polymerizing catalyst which comprises subjecting uncondensed cracked gases to contact with debutanized cracked distillate to absorb substantial amounts of three and four carbon atom hydrocarbons. 75

- blending the resultant enriched distillate absorbent with unstabilized cracked gasoline, fractionating the blend to remove propane and lighter compounds, subjecting the blend freed from said propane and lighter compounds to treatment with an aqueous solution of an alkali, and further fractionating the alkali-treated blend to produce a butane-butene fraction.
2. A process for the production and purification of butane-butene fractions to render them suitable for contacting with a polymerizing catalyst which comprises subjecting uncondensed cracked gases to contact with debutanized cracked distillate to absorb substantial amounts of three and four carbon atom hydrocarbons, blending the resultant enriched distillate absorbent with unstabilized cracked gasoline, fractionating the blend to remove propane and lighter compounds, cooling the blend freed from said propane and lighter compounds to a temperature of the order of 120° F., subjecting the cooled blend to treatment with an aqueous solution of an alkali, and further fractionating the alkali-treated blend to produce a butane-butene fraction.
3. A process for the production and purification of butane-butene fractions to render them suitable for contacting with a polymerizing catalyst to produce substantial yields of octenes, which comprises subjecting uncondensed cracked gases to contact with debutanized cracked distillate to absorb substantial amounts of three and four carbon atom hydrocarbons, blending the resultant enriched distillate absorbent with unstabilized cracked gasoline, fractionating the blend to remove propane and lighter compounds,

cooling the fractions of said blend freed from said propane and lighter compounds to a temperature of the order of 120° F., subjecting said cooled fractions to treatment with a partly spent aqueous solution of an alkali, separating the treated fractions from the aqueous alkali and utilizing a portion of the latter as said partly spent solution, and distilling the alkali-treated fractions to produce an overhead fraction consisting substantially only of butanes and butenes. 5

4. A process which comprises scrubbing cracked hydrocarbon gas with debutanized gasoline to absorb in the latter C₄ components of the gas, combining the thus enriched gasoline with unstabilized cracked gasoline containing C₄ hydrocarbons, treating the resultant mixture with aqueous alkali solution to separate impurities from the gasoline and from the normally gaseous hydrocarbons contained in said mixture, and then stabilizing the thus treated mixture to remove C₄ 15 hydrocarbons therefrom. 20

5. A process which comprises scrubbing cracked hydrocarbon gas with debutanized gasoline to absorb in the latter C₄ components of the gas, combining the thus enriched gasoline with unstabilized cracked gasoline containing C₄ hydrocarbons, treating the resultant mixture with aqueous alkali solution to separate impurities from the gasoline and from the normally gaseous hydrocarbons contained in said mixture, and then stabilizing the thus treated mixture to remove C₄ hydrocarbons therefrom and supplying a portion of the stabilized mixture to the scrubbing step as an absorbent therein. 25 30
